E. MURRAY ET AL

RESET VALVE FOR TRAIN CONTROL MECHANISM

Filed Dec. 13, 1924

Ch. Farle

UNITED STATES PATENT OFFICE.

EARLE MURRAY AND WILLIAM B. MURRAY, OF DANVILLE, ILLINOIS, ASSIGNEES
TO THE MILLER TRAIN CONTROL CORPORATION, OF STAUNTON, VIRGINIA, A COR-
PORATION OF VIRGINIA.

RESET VALVE FOR TRAIN-CONTROL MECHANISM.

Application filed December 13, 1924. Serial No. 755,760.

This invention relates to train control mechanism, and more particularly to a positive stop valve adapted to be opened when the control mechanism is actuated and prevent return of the control mechanism to its normal position until the stop valve is reset.

An object of the invention is the provision of an attachment for train control systems of the general type shown in the patent to 10 William B. Murray, granted October 3, 1922, No. 1,431,025, in which a piston is arranged in a cylinder, the piston being connected to the engineer's air brake valve or other mechanism, the pressure in the top and 15 bottom of the piston being normally balanced to retain the piston in a set position, and means actuated by the track conditions are provided to unbalance the pressure, which attachment is connected to the said 20 cylinder and is adapted to be actuated by the unbalancing of the pressure in the cylinder to open a valve and prevent a balanced pressure from being re-established in the cylinder until the valve is closed.

25 More specifically, the invention comprises a cylinder having a piston arranged therein, one end of the cylinder being connected to the main reservoir of the train system and the other end being connected to the main 30 cylinder of the train control mechanism whereby a balanced pressure will normally exist in the re-set valve cylinder. The cylinder is provided with an outlet port communicating with the atmosphere and having 35 a valve therein adapted to be moved to an open position upon movement of the piston, and suitable means are provided for closing the valve either manually or through the provision of an electric circuit adapted to 40 be established by closing a switch or by an automatic governor when the train comes to a stop.

In the accompanying drawings, we have shown one embodiment of the invention. In 45 this showing:

The figure is a diagrammatic side elevation of a train control system of the type shown in the copending application of William B. Murray, filed April 21, 1922, 50 Serial No. 555,854, showing the re-set valve connected thereto.

Referring to the drawings, the reference numeral 1 designates the casing of an en-

gineer's air brake valve of the usual construction which is mounted in the vehicle at 55 any convenient point, generally in the engineer's cab. A shaft (not shown) extends through this casing and is provided with a lever 2 to permit revolution of the shaft to open or close the valve and apply the brakes. 60 The control apparatus consists of a cylinder 3 which is closed at its lower end and is provided with a port 4 communicating with the top of the cylinder to admit air or other fluid under pressure. This port is connected 65 to a source of fluid under pressure, such as the air reservoir, by means of a pipe 5. The upper end of the cylinder is closed by a head 6, which is provided with a central boss 7. A piston 8 is arranged in the cylinder and 70 this piston is provided with a piston rod 9 extending through the boss 7. The piston rod is adapted to be surrounded by suitable packing retained in position by means of a packing gland 10. The inner end of the boss 75 is surrounded by a suitable strip of packing 11. A casing 12 surrounds the piston rod and this casing carries a bracket 13 adapted to support a steel roller 14 mounted on a pin 15. A chain 16, preferably of steel, 80 is connected to the upper end of the piston rod. The chain may be connected to the piston rod in any suitable manner. A drum 17 is secured to the shaft of the air brake valve and the other end of the chain is secured to 85 this drum. The drum is provided with a depending lug or pin 18, shown in dotted lines, which is adapted to engage one side of the air brake lever to limit the revolution of the drum. A cover plate 19 is connected 90 to the casing 12 and extends over the drum and the horizontal portion of the chain.

A valve casing 20 is arranged adjacent the main cylinder. This casing is provided with 95 a main inlet port 21 communicating with a passage 22 in the cylinder wall extending to the bottom of the cylinder. The piston is provided with a restricted passage 23 whereby the lower portion of the cylinder 100 communicates with the upper portion to establish a balanced pressure therein. The valve casing is provided with a main valve seat 24 arranged in a central port 25, connecting the inlet passage to a chamber 26. 105 The bottom of the chamber is closed by a

plate 27. This plate is provided with an opening having a valve seat formed on its upper end. A chamber 28 is arranged below the plate and the side wall of the chamber is provided with an opening adapted to receive a whistle 29. A valve member 30 is arranged in the chamber 26 and is provided with a valve 31 adapted to engage the valve seat 24. The lower portion of the valve member is also provided with a valve adapted to engage the seat formed in the opening in the plate 27. The valve member is provided with a stem 32 extending into the chamber 28. The main valve 31 is normally in open position as shown, and is adapted to be controlled by a magnet 33. As shown, this magnet is provided with a core 34 which is raised when the magnet is energized. A pin 35 is arranged above the core and is adapted to be lifted by the core to raise the valve member 30.

The upper end of the valve casing is provided with a port 36, communicating with the top of the cylinder. The valve casing is closed by a cap 37, the interior of which is hollow, forming an auxiliary chamber 38. This chamber is provided with an outlet opening 39, communicating with a passage 40. The main valve chamber 26 is provided with an outlet 41, communicating with a conduit 42. The passage 40 communicates with the conduit through the passage 41. The passage 37 is provided with a valve seat normally engaged by a valve 43. This valve is provided with a depending stem 44, which projects into the inlet passage 25 and is adapted to be engaged by the main valve when the main valve is raised.

The conduit 42 communicates with a shoe 45 arranged on the locomotive or tender at any convenient point and adapted to engage ramps arranged at spaced intervals along the track. The shoe is mounted in a bracket 46, secured to a part of the vehicle and arranged relatively close to the ground. As shown, the shoe comprises a substantially cylindrical member 47 having flanges 48 formed on opposite sides. These flanges are provided with slots 49 to permit vertical adjustment of the shoe in assembling. Bolts 50 pass through these slots and are received in suitable openings in the bracket. The shoe is insulated from the bracket to insulate it from the vehicle. A piston 51 is arranged within the cylinder, the piston being provided with suitable packing to prevent leakage of air. The conduit 42 communicates with a port 52 formed in an enlargement 53 on the front of the cylinder and this port communicates with the interior of the shoe by means of a chamber 54. The cylinder is provided with an outlet opening 55.

The piston is provided with a piston rod 56, having a substantially L-shaped plate

57 on its lower end which forms the contact member of the shoe. The shoe is connected to the magnet by means of a lead wire 58.

The re-set valve consists of a cylindrical casing 59 mounted on a locomotive at any convenient point and communicating with the main reservoir by means of a pipe 60. As shown, the pipe 60 is connected to pipe 5 by a coupling 61. The lower end of the casing is provided with a port 62 connected to a pipe 63 communicating with the main cylinder 3 of the control apparatus. A piston 64 is arranged in the cylinder and this piston is provided with a passage 65 whereby a balanced pressure will normally exist in the cylinder. The top of the cylinder is closed by a plug 66 having a central opening through which the piston rod 67 extends. A sheet of packing 68 is arranged around the lower end of this opening. The lower portion of the valve casing is provided with a chamber 69, communicating with the main cylinder through a restricted passage. This passage is provided with a valve seat adapted to be closed by a valve 70 having a stem 71 projecting upwardly to a point adjacent the piston. A spring 72 normally retains the valve in closed position. The chamber 69 is provided with a passage 73 communicating with an outlet port 74. The passage 72 is provided with a valve seat 75 adapted to be engaged by a valve 76. A magnet 77 is arranged beneath the valve 76 and this magnet is provided with a core 78 adapted to be raised when the magnet is energized. As shown, the core is provided with an extension 79, projecting from the bottom end of the casing to permit manual operation of the valve 76. The magnet 77 is connected to a local circuit consisting of a source of current 80 in which a push button or hand operated switch 81 may be arranged. As shown, a lead wire 82 extends from the source of current through the switch 81 to one side of the magnet and a lead wire 83 extends from the other side of the magnet back to the source of current. A governor 84 may be arranged therein to prevent the circuit from being closed except when the vehicle is stopped.

The operation of the main control apparatus is substantially the same as that described in the prior patent to William B. Murray, heretofore referred to. Normally, the pressure on each side of the piston 8 is equal and the parts remain in the position shown in the drawings. At each ramp, the shoe is lifted and the air in the conduit 42 is exhausted. If the valve 31 is in open position, the fluid is exhausted from the bottom of the cylinder. However, when the train approaches a clear block, the ramp is energized and current is fed through the shoe to the magnet by the wire 58 raising the valve 31 and preventing the air from

being exhausted from the cylinder. At the same time, the auxiliary valve 43 is raised to permit air to pass through the passage 36 and the passage 40 to replenish the supply 5 exhausted from the conduit 42. When a dead ramp is encountered, the valve 31 remains in an open position and the piston 8 moves downwardly in the cylinder, due to the pressure of air on its upper surface, 10 revolving the drum 17 and thus turning the engineer's air brake lever to apply the brakes.

The re-set valve is adapted to be actuated whenever the air in the lower portion of the 15 main cylinder is exhausted. Normally, the pressure is equalized in the re-set valve cylinder 59 due to the fact that the upper end of the cylinder is in communication with the main reservoir through the pipes 5 and 60 20 and the lower end is in communication with the bottom of the main cylinder through the pipe 63. The port 65 in the piston permits the pressure to equalize. The valve 70 is normally retained in closed position by the 25 spring 72 and the passage 74 is thus disconnected from the pipe 63. When the pressure falls in the cylinder 3, the pressure in the lower portion of the re-set valve cylinder is decreased and the pressure on the upper 30 surface of the piston 64 moves it downwardly, causing the lower face of the piston to engage the valve stem 71, thus opening the valve 70. When the valve 70 is open, the bottom of the cylinder 3 is in communication 35 with the atmosphere through the pipe 63, the valve cylinder 59, chamber 69, passage 73 and port 74. As long as this valve remains in an open position, the brakes will be held in an applied position regardless of the position 40 of the valve 31, and even after the ramp has been passed, the engineer is unable to proceed until the re-set valve has been set. The re-set valve casing may be arranged outside the engineer's cab, if desired, in order 45 to compel him to leave the cab to reset the valve. If the re-set valve is to be manually operated, the core 78 is moved upwardly by forcing the extension 79 upwardly, raising the valve 76 to its seat. This closes the port 50 74 and the pressure immediately begins to build up in the bottom of the main cylinder 3 and in the bottom of the re-set valve cylinder. As soon as the pressure is equalized, the pistons 8 and 64 are raised and the valve 55 70 closed by the spring 72.

The manually controlled switch 81 can also be employed to set the re-set valve. By closing the switch, the magnet 78 is energized, raising the core in the manner just 60 described to close the valve 76. When the speed governor 84 is connected to the circuit, it is adapted to break the circuit when the governor is moving and permits the local circuit through the re-set magnet to be closed

only when the vehicle is in a state of rest or 65 at some predetermined speed.

It is to be understood that the form of our invention herewith shown and described is to be taken as a preferred example of the same, and that various changes in the shape, 70 size, and arrangement of parts may be resorted to without departing from the spirit of the invention or the scope of the subjoined claims. 75

We claim:

1. In a device of the character described, a casing, a movable member mounted in said casing and operatively connected to a part of the vehicle control mechanism, means for maintaining a balanced pressure in said casing, means controlled by the movement of the vehicle to release the pressure in one end of said casing, and a valve adapted to be opened by the release of pressure in one end of said casing and prevent re-establishment of a balanced pressure in said casing while said valve is in open position. 80

2. A device constructed in accordance with claim 1 wherein means are provided for independently closing said valve. 90

3. A device constructed in accordance with claim 1 wherein means are provided for independently closing said valve, said means being inoperative when the vehicle is moving faster than a predetermined speed. 95

4. In a device of the character described, a casing, a movable member mounted in said casing and operatively connected to a part of the control mechanism of the vehicle, means for maintaining a balanced pressure in said casing, means controlled by the movement of the vehicle to release the pressure in one end of said casing, an auxiliary casing connected to the said end of said casing, 100 the other end of said auxiliary casing being connected to the main air reservoir to maintain a balanced pressure therein, a piston mounted in said auxiliary casing, one end of said casing being provided with an outlet, 105 and a valve arranged in said outlet and adapted to be opened by the movement of said piston. 110

5. A device constructed in accordance with claim 4, wherein said valve is normally maintained in closed position by a spring and said spring is compressed when said valve is opened by said piston. 115

6. A device constructed in accordance with claim 4 wherein a magnet is arranged adjacent said valve and said magnet is provided with a core adapted to engage said valve when said magnet is energized to move said valve to a closed position. 120

In testimony whereof, we affix our signatures. 125

EARLE MURRAY.
WILLIAM B. MURRAY.
